UNITED STATES PATENT OFFICE.

CHARLES H. MILLER, OF LIBERTY TOWNSHIP, JEFFERSON COUNTY, IOWA.

MAN LIFT.

Application filed October 25, 1921. Serial No. 510,212.

To all whom it may concern:

Be it known that I, CHARLES H. MILLER, a citizen of the United States, residing in Liberty Township, in the county of Jefferson, State of Iowa, have invented certain new and useful Improvements in Man Lifts, of which the following is a specification.

This invention relates to elevators such as 10 are actuated by the passenger, and more especially to the brakes therefor; and the object of the same primarily is to simplify and yet improve the construction set forth in my United States Patent Number 15 1,382,211 issued June 21, 1921. Substantially the same principle of operation prevails herein, but for the toggle mechanism and linkage of my former patent I have substituted a simpler automatic brake here- 20 in composed of a plurality of triangles linked to rock in unison and apply the brakes with great power excepting only when the carriage contains a passenger of average weight.

25 Structural details are simplified so that greater strength is secured with less total weight. The reader is referred to my former patent for a full description of the operation of a lift of this kind. The following specification gives the operation briefly and the structure of parts as shown on the accompanying drawings, in which—

Figure 1 is an elevation of this manlift showing the position the parts assume when 30 its platform bears a passenger of average weight, the brakes being released.

Fig. 2 is an elevation of the upper portion of the lift slightly modified, the brakes here being applied.

40 Fig. 3 is an enlarged detail of the preferred form of rocker, showing how its cam face passes the roller under the impulse of pressure on the pedal.

Figs. 4 to 8 are sectional views taken on 45 lines in Fig. 1 bearing the same numbers respectively.

Fig. 9 is an elevation and Fig. 10 a section—both enlarged—to show the crown and the attachment of the yokes to the master bolt.

Fig. 11 is a plan view of the platform, showing some of the floor plates removed.

The car frame is a rolled steel T-bar whose shank is cut and mitered so that the

bar can be bent twice at right angles to 55 produce a horizontal sill 3 standing below the platform and two upright side arms 1, 1 connected by a pair of beams 2 of U-shape with their backs toward each other but spaced for the parts which must pass between them; thus the entire frame is 60 U-shaped in side elevation with its arms connected near their upper ends, as seen in Fig. 1. The heads of the side arms 1 are outermost, and as the car ascends and descends these heads travel inside steel strips or bands 4 secured within and extending the full length of the elevator shaft; also provision may be made to have said heads engage the usual shaft guides if desired. The 65 side bars 1 are reinforced at their upper ends by strips 6 secured to the edge of the T-shank, and also secured between the beams 2 as seen in Fig. 7; and these strips stand within the upper portion or head of 70 the car. Within its lower portion is movably mounted the carriage which includes the platform and its supports. Links 7 loosely connect the upper ends of the side arms 1 with a crown (see Figs. 9 and 10) 75 made up of two L-plates 8 riveted together and pierced by a master bolt 9, and two yokes 10 hang from this bolt with their arms diverging in pairs, being secured in plates 11 as seen in Figure 8. Spaced 80 spreader bars 12 are secured beneath the plates, and they have rollers 13 contacting with the side arms 1 as shown. From said plates and bars hang U-shaped truss rods 14, each having its center passing beneath 85 the platform and supporting it by a strut 15. The spreader bars are further connected with the crown by an upright bar or blade 16 bolted between the plates 8, passing thence loosely between the beams 2, and 90 welded as at 17 between the centers of the bars 12; and this blade has a shoulder 18 for a purpose to appear.

The platform (Figures 1 and 11) may be variously made. As here shown, four joists 100 20 are held parallel by cross bars 21 of L-iron, and floor boards or plates 22 are secured thereon. Brackets 23 carry rollers 24 serving as guides on the side arms 1; and Figure 11 shows blocks 25 which may 105 be employed when the manlift is used in a house, these blocks sliding within the walls of the shaft. Rising from the sill 3 through

the platform is a standard or bracket 26 carrying a pulley 27 for an operating rope R secured at its upper and lower ends within the elevator shaft and making a double 5 or S-bend within the car. After leading under this pulley, the rope passes upward over another pulley 28 pivoted at 29 to one of the beams 2, and thence downward within the shaft; and hence the operator always 10 has a stretch of rope on which to draw downward, whether he desires to ascend or descend.

The T-head of each side arm 1 opposite the reinforce is enclosed in a U-bar constituting a brake shoe 31 and the contiguous faces of the shoe and jaw may have appropriate brake lining if desired. The webs of each shoe pass the edges of the jaw and are connected by bolts 30 passing through 20 slots 32 in the T-stem so that the shoe may move horizontally but not longitudinally with respect to the jaw. On the uppermost bolt are pivoted twin triangular brake levers 33, and on the other bolts other twin 25 but smaller triangles 34, all pivots being at the centers of the bases of the triangles; while links 35 are pivoted to the triangles and cause them to turn in unison on their pivots. The inner ends of the larger triangles or levers 33 straddle the bar 16 and have rollers 37 which underlie the L-plates 8 of the crown. If desired, the link 35 may be extended downward as at 35' and a contractile spring 38 connects it with a bracket 30 or ear 39 on the frame, as seen in Figure 1.

From a counterbalancing weight W a cable C leads over pulleys down the shaft, and is itself forked or is connected with fork arms 33' which in turn are connected 40 with the brake levers 33. The parts are of such weight that, when a passenger of average weight steps upon the platform as is supposed to be the case in Fig. 1, the bar 16 is moved downward with respect to the 45 head which latter is held to the straps 4 by the grip of the brakes, all triangles turn on their pivots, and the brakes are automatically released; hence the weight W should counterbalance the car and a passenger of average weight. If a child or 50 a person below average weight steps onto the platform, the parts remain as in Fig. 2 and the car at rest clamped to the strips 4; hence additional weights must be placed on 55 the platform to bring the effective weight of the passenger up to average, and these can be placed on the ground floor and at each landing for the purpose. If an over-weight passenger steps on the platform, the levers 60 33 are swung down beyond the horizontal position shown in Fig. 1, and the brakes are automatically applied; also this occurs if the cable C should part under any condition. Hence I provide an internally threaded tube 65 40 carried by the beams 2, a screw 41 en-

gaging the same from below and extending down between the spreader bars 12 and through a strong spring 42, and a crank handle 43 at the lower end of this screw above but within reach of an adult standing on 70 the platform. By running up this screw and putting the spring under more or less tension, the effect of over-weight is overcome.

The foot-controlled brake mechanism includes means for drawing the shoes into gripping contact with the straps by spring pressure, and a pedal near the platform connected with such means whereby it may be overcome or eased off by the passenger at 80 will. A U-shaped brake rod 50 leads inward from the left shoe and is connected with the upper end of a brake lever 51, while a U-shaped brake rod 52 leads inward from the right shoe and is connected with said 85 lever at a lower point. A link 53 connects the lower end of said lever with a point near the upper angle of a substantially triangular rocker 54, and a second link 55 leads from just above such point inward and is 90 connected with a contractile spring 56 attached to some part of the mechanism; hence the spring normally applies the brakes, while also it normally swings the lower angle 58 of the rocker away from the bar 16 95 as seen in Fig. 2. Near this angle the rocker has a pin 57 moving in a slot 59 in the beams 2, or the pin 67 may move in loop straps 69 as seen in Fig. 3 and itself serve the purpose of the angle 58 as described below. Just below the remaining angle 60 of the rocker it is formed with a cam face 61 riding over a roller or pin 62, and the angle 60 clears this roller when the angle 58 (or pin 67) swings over the shoulder 18 as seen 100 in Fig. 1. Pivoted to the rocker near the cam face is a link 63 which leads to a lever 64, and from the latter a rod 65 leads downward to a pedal 66 mounted near the platform. 110

With an underweight person on the platform, the foot brakes may not be released, but as soon as the platform descends (as described above) until the shoulder 18 passes the rocker the passenger may use the pedal 115 at will to release or ease off the foot brakes and permit the lift to ascend or descend as he wishes.

What is claimed as new is:

1. In a manlift, the combination with a 120 car including a head and carriage traveling on the shaft guides, a weight substantially counterbalancing the car and the average passenger, and a cable leading from the weight; of rocking brake shoes in said head 125 coacting with said guides and having levers, said cable being attached to said levers for swinging them and applying the shoes when the car has no passenger, and connections between said levers and the carriage whereby 130

- the weight of the average passenger will release the brakes.
2. The structure specified in claim 1 plus: triangular rocking brakes in said head, and connections between them and said brake levers, whereby all brakes work in unison.
3. The structure specified in claim 1 plus: means whereby the levers are swung and the shoes applied when the cable parts.
4. The structure specified in claim 1 plus: means whereby the levers are swung and the shoes automatically applied by an overweight passenger, and means whereby he can nullify his excess effective weight.
5. The structure specified in claim 1 plus: an upright bar rising from the carriage between said levers and having a crown overlying their inner ends, and links loosely connecting the crown and head.
6. The structure specified in claim 1, plus: a second brake mechanism normally applied, and passenger control mechanism therefor leading to the carriage.
7. The structure specified in claim 1 plus: a second brake mechanism, a spring for normally applying the same, releasing means therefor leading to the carriage, and means carried by the carriage for preventing the action of the releasing means until said carriage descends with respect to said head.
8. The structure specified in claim 1 plus: a second brake mechanism including a rocker, means for normally applying this brake, releasing means therefor leading to the carriage, and a bar rising from the carriage and having a shoulder preventing the movement of the rocker to release this brake until said carriage descends with respect to said head.
9. In a manlift, the combination with a car comprising a head and a carriage movably connected and traveling on guides, brake mechanism in the head for application to said guides by the rise or descent of the carriage with respect to the head, a cable leading from a weight substantially counterbalancing the car and the average passenger, and connections between said cable and brake mechanism whereby the latter is released by the weight of the average passenger only; of a second brake mechanism within the head, a spring for normally applying it to said guides, passenger operated means for releasing this brake, and a bar rising from the carriage and having a shoulder so disposed as to prevent the release of this brake until the carriage is loaded up to the weight of the average passenger.
10. In an elevator brake, the combination with guide strips fixed in the shaft; of the car whose frame includes side arms traveling inside said strips, U-shaped brake shoes enclosing said strips and their webs passing the arms, triangular brake levers pivoted to said webs and coacting with said arms, means for rocking the levers, and independent means for drawing said shoes inward.
11. The structure specified in claim 10, plus: the first means being controlled by the load on the elevator and the second under the control of its passenger.
12. The structure specified in claim 11, plus: means to prevent the release of the passenger-controlled brake while the car is empty or loaded with less than the weight of the average passenger.
13. In an elevator brake, the combination with guide strips fixed in the shaft, and the car whose frame includes T-shaped side arms with their heads traveling inside said strips and constituting jaws and beams rigidly connecting the T-shanks; of U-shaped brake shoes enclosing said strips and their webs passing the edges of said jaws, and means for drawing the shoes toward the jaws.
14. The structure specified in claim 13, plus: said T-shanks having horizontal slots, bolts through such slots connecting the webs of the shoes, twin triangles pivoted on said bolts with their bases coacting with the T-heads, and means for rocking the triangles.
15. In an elevator brake, the combination with the shoes, brake lever, and connecting rods; of a substantially triangular rocker mounted on a movable fulcrum near one angle and having a cam face near another, a link connecting said lever with the rocker near its remaining angle, means for normally applying the brakes, and manual control means connected to the rocker near its cam, the whole for operation as specified.
16. The structure specified in claim 15, plus: a roller over which said cam face travels when the control means is actuated whereby the fulcrum point changes, and a shoulder coacting with the angle near the fulcrum at this time, for the purpose specified.
17. An elevator structure comprising a U-shaped frame, guides for its side arms, a platform movably mounted in the lower portion of the frame, spreader bars movably mounted therein at a higher point, connections between the platform and bars, a crown above the bars and connected with them, levers pivoted in the frame with their inner ends underlying said crown, and a supporting cable branched and connected with said levers.
18. The structure specified in claim 17, plus: the frame being of T-iron with its head next said guides, and brake shoes enclosing the guides and the T-heads of the side bars of the frame, said levers actuating such brakes.
19. An elevator structure comprising a U-shaped frame of T-iron bent into a sill and two upright side arms, the T-heads of

the latter adapted to slide on guides in the shaft, beams connecting the arms near their upper ends, spreader bars below the beams having rollers movably engaging said arms,
5 an upright central bar rising rigidly from the spreader bars and having a crown, A-shaped yokes whose angles are attached to the crown and whose arms are attached to

the spreader bars, a platform above the frame sill and having rollers movably en- 10 gaging its arms, and truss rods hung from the spreader bars with their centers underlying the platform.

In testimony whereof I affix my signature.

CHARLES H. MILLER.
